UNITED STATES PATENT OFFICE.

HARRY SILVERMAN, OF MINNEAPOLIS, MINNESOTA.

IRONING BOARD AND STEAMER.

Application filed December 17, 1925. Serial No. 75,937.

This invention relates to an ironing table and particularly to an ironing table with which steam is used. As is well known to those skilled in the art, it is the common practice in cleaning and pressing establishments and other places where cloth goods are pressed, to steam the goods after they are pressed in order to eliminate and prevent a shiny or glossy appearance on the cloth. It has heretofore been the common practice in many cleaning and pressing establishments to make a separate operation on a separate machine of the steaming after the clothes were pressed. This takes lots of the operator's time and necessitates special apparatus.

It is an object of this invention to provide an ironing table on which fabrics can be pressed and simultaneously or subsequently steamed.

It is a further object of the invention to provide an ironing table comprising an ironing board having a comparatively smooth surface and provided with means disposed below said surface for supplying steam, means also being provided for distributing the steam over the surface of the board and the board having the usual fabric covering on which the pressing is done, said board preferably being of metal to be easily heated by the steam.

It is also an object of the invention to provide an ironing board having a groove extending longitudinally thereof in which a perforated steam supply conduit is disposed, adapted to direct the steam downwardly in said groove, together with heating means in said groove to heat the board and dry any moisture or condensation of steam.

It is also an object of the invention to provide an ironing table having a board to which steam is supplied together with means adapted to be easily and conveniently manipulated by the operator for controlling the supply of steam.

These and other objects and advantages of the invention will be fully set forth in the following description made in connection with the accompanying drawings in which like reference characters refer to the same parts throughout the different views, and in which,

Fig. 1 is a view in side elevation of the device;

Fig. 2 is a plan view of the device with some portions broken away;

Fig. 3 is a view in vertical section taken on the line 3—3 of Fig. 2, as indicated by the arrows;

Fig. 4 is a vertical section on an enlarged scale taken on the line 4—4 of Fig. 1, as indicated by the arrows;

Fig. 5 is a plan view of a portion of the steam pipe used;

Fig. 6 is a view similar to Fig. 2 showing a modification;

Fig. 7 is a vertical section taken on the line 7—7 of Fig. 6, as indicated by the arrows;

Fig. 8 is a vertical section taken on the line 8—8 of Fig. 7, as indicated by the arrows; and

Fig. 9 is a vertical section taken on the line 9—9 of Fig. 7, as indicated by the arrows.

Referring to the drawings, particularly Figs. 1 to 5, an ironing table is shown comprising the ironing board 6. While this board may be variously supported, in the embodiment of the invention illustrated, the same is shown as having downwardly projecting lugs 6^a on its undersurface adapted to be received in socket members 7 which are carried, respectively, at the upper ends of vertical leg members 8 arranged in rectangular relation and preferably tied together by the members 9. The ironing board 6 is of the customary shape, and while this shape may be varied, in the embodiment of the invention illustrated, the board is shown as having its sides converging toward one end. Said board 6 has a comparatively smooth top surface, one portion 6^b of which, at the rear end of the board, is somewhat higher than the remaining portion 6^c. The portion 6^c of the board has a trough or groove 6^d formed therein illustrated as triangular in shape and this groove is deeper at its end adjacent the wide end of the board than it is at the end adjacent the narrow end of the board so that any moisture therein would drain toward the wide end of the board. Disposed in the groove 6^d is a conduit 10 having a multiplicity of small perforations 10^a in its undersurface. The pipe 10 is threaded at one end and received in a threaded hole 6^e at the rear end of the groove 6^d and the pipe can be conveniently inserted in groove 6^d by being passed through a hole 6^f at the forward end of the groove 6^d, the forward end of the pipe 10 preferably being closed and a plug 11 also being screwed into the end of the hole 6^f.

100
105
110

A hole 6^c extends through the bottom of the board 6 adjacent the deep end of groove 6^a and the set screw 12 is threaded into this hole. The hole 6^c and pipe 10 communicate with a pocket 6^b formed beneath the board and a pipe 13 extends into the rear side of pocket 6^b. The pipe 13 is adapted to be connected to a source of steam supply and has therein a controlling valve 14. The valve 14 has an operating lever 15 adapted to open and close the valve, which lever is connected to a flexible rod 16 extending through the conduit 17 and connected at its other end to one end of a treadle 18. The treadle 18 is pivoted intermediate its ends in a bracket 19 secured to the floor and the end of the treadle connected to rod 16 is urged downward by a compression spring 20. When the free end of the treadle 18 is in its upper position to which it is moved by spring 20 the valve 14 is closed.

Disposed over the groove 6^a is a strip 21 of fine reticulate material, such as fine metal screen or fine wire cloth. The strip 21 is somewhat wider than the maximum width of groove 6^a and while the same may be held in place by any suitable means, in the embodiment of the invention illustrated, the same is shown as held by a plurality of screws 21^a having their heads countersunk into the board 6. A layer of reticulate material 22, similar to the material of strip 21, extends over the strip and over the portion 6^c of the board 6, the edges of the layer 22 being bent around the side edges of the board and around the small end thereof. The usual layer of fabric material 23 is placed over the screen 22 and the article to be ironed is placed or arranged on this fabric material or pad 23. The board 6 is made of metal. While various metals, or metals which are good conductors of heat, may be used, in practice, the board has been made of aluminum.

In operation, the ironing board described will be used in the customary way and the fabrics pressed thereon by means of a hand iron. The portion 6^b at the end of the board will form a convenient place for irons to rest when hot and not in use. When it is desired to steam the garments the operator will step on the free end of the treadle 18. This will open valve 14 and steam will be forced into the pipe 10 and will issue through the perforations 10^a therein downwardly into the groove 6^a. This steam will pass upward through the screen fabric 21 and 22 and through the cloth cover 23. The board will be heated by this steam and the steam will rise from groove 6^a and thus be applied to the cloth article being pressed on the board. The screens 21 and 22 tend to distribute the steam over the entire surface of the board. This steam being applied to the garment and the same pressed, any gloss or

shine on the cloth will be prevented. The steam, as stated, heats the metal board and there is little tendency for the board and the applied steam to cool the irons. The irons used therefore on applicant's board remain hot for a much longer time than is usual when another kind of board is used. The amount of steam used can be nicely regulated by the operator. The temperature of the board will quickly dry out any condensation of steam which may occur in the groove 6^a. If an appreciable amount of water should collect in this groove it will run to the deep end of the groove and may be drained through the hole 6^c, if desired. The pocket 6^b will collect any condensation of the steam from the pipe 13.

In Figs. 6 to 9, a modified form of the board is shown. The board 25 is similar in shape to the board 6 having a raised portion 25^b at one end similar to the portion 6^b and will have supporting members 25^a on its bottom similar to the portions 6^a adapted to be received in the members 7 at the top of the legs 8. The board 25 has a groove or trough 25^a extending longitudinally thereof which is of considerable depth and width. The board 25 also has a chamber 25^c formed beneath the portion 25^b with which a live steam pipe 26 communicates, said pipe being adapted to be connected to some suitable steam supply. A live steam pipe 27 communicates at one end with the chamber 25^c and passes longitudinally through the trough 25^a and communicates at its other end with a chamber 25^d formed beneath the narrow end of board 25. The return steam pipe 28 also communicates at one end with the chamber 25^c and at its other end is bent downward and extended into a passage 25^e extending through a boss formed in the rear of the trough 25^a. Another steam pipe 29 also extends longitudinally through trough 25^a between pipes 27 and 28 and has its inner end closed, said pipe 29 being bent downward at its other end to fit in and communicate with a passage 25^h parallel to passage 25^e. A pipe extends from passage 25^h and is connected to pipe 26, a control valve 32 being located therein which may either be operated by hand or controlled by a suitable treadle, as shown for valve 14 in Fig. 1. A drain pipe 30 also communicates with the bottom of trough 25^a at its deep end. The pipe 29 is perforated at its lower side so that steam is delivered to the groove 25^a and directed downwardly therein. It will be noted that the trough 25^a is of much greater depth at the end of the board adjacent the portion 25^b than at the other end of said board. The surface of the board 25, at each side of the groove 25^a, is rabbeted to receive a plate 31 provided with a multiplicity of holes and held in place by suitable countersunk screws. A layer of fine screen

34, such as wire cloth, extends across the entire surface of the board 25, other than the portion 25^b, said material preferably having its edges bent around the sides of the side edges of the board. The usual pad of cloth material 35 overlies the screen and is held by the board in any suitable manner. The steam supply pipe 26 will be controlled by a valve 33 either by hand or in a manner similar to that already described in connection with steam pipe 13 shown in Fig. 1.

In operation, the board shown in Figs. 6 to 9 will be used for pressing and steaming. Valve 33 will be open during the operation 15 of the board and the board will be heated by the steam passing through pipes 27 and 28. When it is desired to steam with the board the valve 32 will be opened momentarily and steam will be directed downwardly into trough 25^a. The temperature in this trough is quite high, owing to the heating pipes 27 and 28 and any condensation or moisture from the steam admitted through pipe 29 will be quickly dried. Substantially dry steam will therefore pass upwardly through the perforations in plate 31 through the screen 34 and through the pad 35. The steaming of the cloth and articles being operated upon will thus be accomplished. A serious objection has existed to some steaming devices of the prior art where the steam was projected directly upon the cloth. This resulted in a spray of moisture of condensation on the cloth. 30 This effect is avoided in applicant's device by directing the steam downwardly in trough 25^a and having heating means therein for drying condensation.

From the above description it is seen that 40 applicant has provided a simple and efficient steaming apparatus for cloth articles while the same are being pressed. By the use of applicant's board, the steaming is effected simultaneously with the pressing and if additional steaming is required this can be done by merely placing the cloth articles in contact with the board and charging steam thereinto. It is sometimes desired to steam the clothing slightly after 45 pressing and then brush the same. In pressing establishments it has heretofore been the practice to have a separate steaming board and each pressing operator would have to make a trip to this board to perform steaming operations. With applicant's apparatus this trip to a separate board is eliminated and the work is thus greatly facilitated. The heated steam pipes

27 and 28 keep the metal board at high temperature so that the heat in the irons is 60 conserved and the pressing operation improved.

It will, of course, be understood, that various changes may be made in the form, details, arrangement and proportions of the parts without departing from the scope of applicant's invention, which, generally stated, consists in a device capable of carrying out the objects above set forth, in the novel parts and combinations of parts disclosed and defined in the appended claims. 65

What is claimed is:

1. An ironing table comprising a board having a comparatively smooth top surface, said board having a trough extending longitudinally in said surface, means for delivering steam downwardly in said trough, means for distributing the steam delivered over the top surface of said board and heating means extending longitudinally of said board in said trough to dry condensation from the steam delivered downwardly 75 therein.

2. An ironing table comprising a board having a comparatively smooth top surface 85 with a single longitudinal groove therein, a steam heating conduit passing longitudinally through said groove, a return heating conduit receiving from said first mentioned conduit, passing longitudinally 90 through said groove and discharging outwardly from said board, a steam conduit within said groove having apertures therein through which live steam may be admitted to said groove and means for conducting the steam discharged into said groove over the top surface of said board. 95

3. An ironing table comprising a metal board having a comparatively smooth top surface with a single longitudinal groove 100 therein, a closed chamber adjacent one end of said groove, a steam heating conduit passing longitudinally through said groove and discharging into said chamber, a return conduit extending from said chamber and passing longitudinally through said groove and discharging outside of said groove at the end thereof opposite to said chamber, a steam conduit within said groove perforated to discharge live steam thereinto and 105 means for conducting the steam discharged into said groove over the top surface of said board. 110

In testimony whereof I affix my signature.

HARRY SILVERMAN.
